UNITED STATES PATENT OFFICE.

JOHN T. ROGERS AND JOHN ROGERS, OF BIRMINGHAM, COUNTY OF WARWICK, ENGLAND, ASSIGNORS TO JOHN B. CLABROUGH, OF SAME PLACE.

BREECH-LOADING FIRE-ARM.

SPECIFICATION forming part of Letters Patent No. 257,764, dated May 9, 1882.

Application filed January 24, 1882. (No model.) Patented in England January 29, 1881.

To all whom it may concern:

Be it known that we, JOHN THOMAS ROGERS and JOHN ROGERS, of Birmingham, Warwickshire, England, have invented a new and useful Improvement in Breech-Loading Fire-Arms, of which the following is a full, clear, and exact description.

Our improvement relates to the cocking mechanism of breech-loading fire-arms operating upon the drop-down principle and having concealed hammers. It is an improvement in that class of guns in which the dropping down of the barrels is made to effect the cocking of the hammers by deflecting a cocking-lever; and it consists in the peculiar construction and arrangement of said cocking-lever in relation to the barrels and the main fulcrum-pin upon which the barrels turn, as will be hereinafter fully described.

Reference is to be had to the accompanying drawings, forming part of this specification, in which similar letters of reference indicate corresponding parts in all the figures.

Figure 1 is a side view of the breech portion of the gun as closed. Fig. 2 is a side view with the gun open for charging, and with the lock-plate broken away to show the cocking-lever. Fig. 3 is a plan view of the gun-body with the barrel detached, and Fig. 4 is a side view of the cocking-lever detached.

a a are the barrels. *b* is the body. *d* are the hammers, and *c c* are the cocking-levers, pivoted in each lock-hole on independent fulcrum-pins *l*, one end of each lever resting under each hammer, and the other ends under the barrels, so that when the barrel is opened for loading the outer ends of the levers are forced down.

f is the base-pin on which the barrels are hung, of the usual form and in the usual position, and which is in no wise interfered with by the action of levers *c*, that by their form and independent center-pins work without passing the center of the base-pin *f*.

Now, we are aware of the fact that a cocking-lever has been fulcrumed on an independent center between the main fulcrum-pin *f* and the hammer, as shown in Patent No. 247,378, and we do not claim this, broadly. It will be

seen, however, that we make the outer end of the cocking-lever of a higher level than the inner or rear end, and extend this outer end over and past the fulcrum-pin *f*, so that it has a range of movement from the barrel to the fulcrum-pin. By this arrangement this end of the cocking-lever in its movement does not pass by or intercept the axis of the fulcrum-pin, as in the patent referred to, and the result is that we are enabled to preserve the full strength and integrity of the fulcrum-pin *f* from side to side of the breech, permitting its easy removability when worn, and making a stronger connection for this end of the breech.

The fore end is of the ordinary construction, but as it takes no part in the operation of cocking need not be further alluded to.

The operation is thus: When the barrels are depressed to open the breech in the act of loading, the pressure on levers *c* at their outer ends raises the opposite ends that are beneath the hammers, and the hammers are thus thrown back. When the breech is again closed the cocking-levers are released, so that they do not hinder the forward movement of the hammers, and, if desired, a small spring may be provided to return the levers to their first position when allowed by the closing of the barrels.

Having thus described our invention, we claim as new and desire to secure by Letters Patent—

The combination, with the breech, the tilting hammer, and barrel, of a main fulcrum-pin, *f*, for connecting the barrel to the breech, extending from side to side of the breech, and the cocking-lever *c*, fulcrumed upon an independent center between the barrel-fulcrum and the hammer, and having its forward end raised to a higher level than its rear end, and extended over and past the main fulcrum-pin, and arranged to play between the same and the lower face of the barrel, substantially as shown and described.

JOHN T. ROGERS.
JOHN ROGERS.

Corrections in Letters Patent No. 257,764.

It is hereby certified that in Letters Patent No. 257,764, granted May 9, 1882, upon the application of John T. Rogers and John Rogers of Birmingham, England, for an improvement in "Breech-Loading Fire-Arms," the name of the assignee and grantee, wherever it appears in said Letters Patent and the printed specification attached to and forming a part thereof, was erroneously written and printed "John B. Clabrough," instead of "John P. Clabrough;" that the correct name is "John P. Clabrough;" that the proper corrections have been made in said Letters Patent to make them conform to the files and records pertaining to the case in the Patent Office.

Signed, countersigned and sealed this 11th day of July, A. D. 1882.

[SEAL.]

A. BELL,
Acting Secretary of the Interior.

Countersigned:

E. M. MARBLE,
Commissioner of Patents.
